Patented Sept. 11, 1928.

1,683,686

UNITED STATES PATENT OFFICE.

JOHN W. McMILLAN, OF MUNCIE, INDIANA.

INHALING DEVICE.

Application filed November 20, 1926. Serial No. 149,580.

This invention relates to improvements in inhaler devices intended to facilitate anesthetizing.

To simplify and facilitate the administration of anesthetics, by inhalation, and to accomplish the anesthetization of the patient in a relatively short period of time, and without danger or undue discomfort or inconvenience to the patient, is the general object of the present invention. More specific purposes of the invention are to provide a device of the kind described which is light in weight, dependable and easy to use, and which occupies relatively small space, is easy to sterilize and cleanse, and is economical of manufacture.

An object of the invention is the provision of an inlet device for introducing anesthetics into a state to be inhaled, so arranged that no injurious particles of the anesthetic will pass directly to the inhaling chamber or cap.

A further object of the invention is the provision of an adjustable connection between parts of the device, whereby an adjustment may be made for supplying fresh air to the anesthetic, under certain conditions.

It is also an object to provide a swivel joint between the mouth piece and the remainder of the device, to meet the position of the patient's face without correspondingly tilting the apparatus as a whole.

The objects of my invention are accomplished by, and the invention is embodied in the new construction, combination and arrangement of parts described in the following specification, and illustrated in the accompanying drawings. The invention is defined in the appended claims.

The several parts of my improved inhaler device are identified by suitable characters of reference applied to them in the different views in the drawings, in which—

Figure 1 is a front view of my improved inhaler device, portions thereof being shown in section.

Figure 2 is a top plan view of Figure 1, a portion of the mouth cap and conduit being broken away.

My invention contemplates the combination and arrangement of a mouth cap or face piece forming an inhaling chamber, an air tight bag, and a conduit extended from the mouth cap into the bag and having its end portion of open formation and adapted to

retain therein, a quota of absorbent material and an air tube extended into the conduit. Structural features consist of the conduit being of divided formation, its body portion 60 being bent at an angle and having perforations in its walls for a closure piece for the free end of the conduit, and a neck element for said bag, having close fitting but removable engagement with said conduit. 65

The invention, in the embodiment shown in the drawings, constitutes an inhaler device of the form, dimensions, and capacity suitable for all general purposes of the practitioner, for minor or major operations; the 70 mouth cap being about five inches in length, the conduit about one inch in diameter, and the bag being about seven inches by eleven inches in size.

The convex or cup like body A of the 75 mouth cap may be made of aluminum, its oval shaped base portion has the marginal flange or lip A' to which is joined the usual flexible pneumatic rim B. The wall structure of the bag consists of an outer ply C 80 of light sheet rubber, and an inner sheet D of closely woven linen or other textile united thereto; the bag thus being flexible and the rubber body sheet thereof being protected from any possible chemical effects of the 85 vapor contents of the bag. The neck portion of the bag is securely retained in a suitable counterbore therefor in the metal neck ring E. The conduit extends from the mouth cap and through the said neck ring 90 and into the bag, and is of divided formation, and consists of a foot piece F and arm piece G. These conduit pieces may be made of light brass tubing and finished in nickel plate. The arm piece G is adapted to rest in movable close fitting engagement with the end portion F' and annular shoulder F² of the foot piece. The free end portion of the arm piece is bent at substantially a right angle to the body portion thereof, and is 95 provided with perforations or openings G', and is closed by a removable plug or cork H. At the bent portion of said arm piece is a boss G² in which is seated an inlet pipe K. This pipe extends suitably beyond the line of the bend of said arm piece and substantially centrally of the depending portion of the arm G, so that there is no possibility of any liquid which may be admitted into the pipe, being conducted directly into 100 the body portion of the conduit, that leads to the mouth cap or inhaling chamber, thus

guarding against any particles of the anesthetic, other than the fumes thereof, being breathed by the patient. Concurrently with the volatilization of the gas in the conduit, 5 there is the mixing with same, of a suitable amount of oxygen drawn thereinto by the respiratory action of the patient. The machine bored neck E has close fitting but movable engagement with the end portion of the 10 arm piece G so that the arm piece may be adjusted vertically for bringing certain of the openings G' above the neck E, thus permitting additional fresh air to enter directly in contact with the anesthetic, which is 15 very essential in controlling the composition of the anesthetic to obtain the proper result, under the use of different anesthetics and varying conditions of different patients, it being understood that the end portion F and 20 the arm piece G form a swivel joint by which the perforated wing of said arm piece and the inlet pipe K may be positioned, somewhat vertically, regardless of the various angles at which the mouth cap may be adjusted to suit different conditions.

The advantages afforded by the simple and efficient construction described are apparent. The several parts besides being extremely economical of manufacture, are easy 30 to assemble or disassemble, are not liable to derangement, and are capable of being thoroughly sterilized and cleansed.

The invention in readiness for use, appears as shown in Figure 1, a quota of gauze 35 or cotton having been disposed in the end portion of the arm piece G and the cork H having been inserted; and the bag having been placed with its neck ring E in engagement with the said arm piece. To practice 40 the invention, the mouth cap is placed in position over the patient's mouth, the operator holding the arm piece G at such angle as may be most convenient. For minor operations requiring only a short period of 45 time, a small quantity of chlorid of ethal is sprayed into the inlet pipe K and which finds lodgment in the absorbent material which is retained in the perforated or foraminous portion of the arm piece. The 50 respiratory action of the patient has such effect, that within a relatively few inhalations of the vapor contents of the conduit and mouth cap,—about six to eight—the patient will be in a state of complete anesthesia. Any possible excess of liquid 55 which may be absorbed in the arm piece settles therein, so that there is no possibility of contact with the face of any irritating element. By my invention it is thus possible 60 for the patient to become anesthetized without experiencing the choking, depressing and sickening effects incident to the use of ordinary inhaling devices.

Where a major operation is to be per-

formed, and in which a longer and possibly 65 an indefinite length of time is required, ether, instead of chlorid of ethal, is used. The operation and function of the invention is so performed, that by its use, a very slight amount of ether is necessary, to maintain the patient in complete anesthesia; 70 moreover the patient returns to normalcy sooner, and is more free from discomfort and muscular strain, than when anesthetized by other devices or methods. The several 75 parts of the device are capable of being easily assembled or disassembled, and of being thoroughly sterilized and cleansed, and occupy relatively small space.

I am aware that minor changes may be 80 made in the structural features and details of my inhaler device, within the scope of the invention as same is defined by the appended claims, without departing from the spirit of the invention or sacrificing any of 85 its advantages.

What I claim as my invention, and desire to secure by Letters Patent, is—

1. In an inhaling device, an inhaling chamber, a hollow foot piece extending from the same in a plane parallel with the open face of the chamber, a substantially L-shaped hollow arm, one end of which has a fitting and rotatably adjustable union with the foot piece and the opposite end having a plurality of openings in longitudinal series therethru, an air-tight bag into which the perforated end of said hollow arm is adjustably mounted to expose a variable area of air openings, whereby a greater or less amount of air may be added to the inhaling medium, and an inlet pipe extending downwardly thru the horizontal portion of the hollow arm substantially centrally of the vertically extending portion of said arm and to a point below the hollow of the horizontal portion of the arm, and above the lower end of the vertical portion.

2. An inhaler device for anesthetizing, comprising a mouth cap; a flexible air-tight bag; a neck ring for said bag; a conduit foot-piece extended from said mouth cap; a conduit arm piece having an L-shaped bend therein and being removably and swingingly united with said foot piece for rotative alignment of the mouth cap, the end portion of said arm piece being adapted to be passed thru and to be retained removably and slidably adjustable in the neck ring of the bag, and having a series of perforations longitudinally of the arm-piece in the walls thereof; a removable closure plug for said arm piece end portion; and an inlet pipe in the bend of said conduit arm piece extended to a location beyond the line of the bend of 125 said arm piece.

JOHN W. McMILLAN.
